CLAIM

The ornamental design for an outdoor LED projector light, as shown and described.

DESCRIPTION

FIG. 1 is a perspective view of an outdoor LED projector light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view thereof taken from the dashed circle labeled "FIG. 8" in FIG. 2;

FIG. 9 is an enlarged view thereof taken from the dashed circle labeled "FIG. 9" in FIG. 3; and,

FIG. 10 is an enlarged view thereof taken from the dashed circle labeled "FIG. 10" in FIG. 4.

The broken lines in the drawings depict portions of the outdoor LED projector light that form no part of the claimed design.

1 Claim, 10 Drawing Sheets
